US00D691607S

(12) **United States Design Patent**
Kim et al.

(10) **Patent No.:** **US D691,607 S**
(45) **Date of Patent:** **** Oct. 15, 2013**

(54) **WIRELESS KEYBOARD**

(75) Inventors: **Dae-Joung Kim**, Seoul (KR); **Woo-Seok Lee**, Seoul (KR); **Sang-Il Park**, Kyunggi-do (KR); **Soo-Jung Ham**, Seoul (KR)

(73) Assignee: **Samsung Electronics Co., Ltd.**, Suwon-Si (KR)

(**) Term: **14 Years**

(21) Appl. No.: **29/390,398**

(22) Filed: **Apr. 25, 2011**

(30) **Foreign Application Priority Data**

Dec. 9, 2010 (KR) 30-2010-0053323

(51) **LOC (9) Cl.** **14-02**

(52) **U.S. Cl.**

USPC **D14/399**

OTHER PUBLICATIONS

U.S. Appl. No. 29/390,422, Applicant Dae-Joung Kim, filed Apr. 25, 2011, title Wireless Keyboard.

Primary Examiner — Deanna L Fluegeman

(74) *Attorney, Agent, or Firm* — Wood, Herron & Evans, LLP

(57) **CLAIM**

The ornamental design for a wireless keyboard, as shown and described.

DESCRIPTION

FIG. 1 is a top front perspective view of a wireless keyboard showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
